UNITED STATES PATENT OFFICE.

CHARLES H. CLARK, OF CRAFTON, PENNSYLVANIA, ASSIGNOR TO CLARK CAR COMPANY, OF PITTSBURGH, PENNSYLVANIA, A CORPORATION OF NEW JERSEY.

ORE DUMP-CAR.

1,136,316.

Specification of Letters Patent.

Patented Apr. 20, 1915.

Application filed October 5, 1908. Serial No. 456,277.

To all whom it may concern:

Be it known that I, CHARLES H. CLARK, a resident of Crafton, in the county of Allegheny and State of Pennsylvania, have invented certain new and useful Improvements in Ore Dump-Cars, of which the following is a specification.

One object of this invention is to so arrange the doors of an ore or other dump car 10 as to provide a bottom or discharging opening of large area.

The invention is here embodied in a pair of doors which close together at the center line of the car and which when opening move bodily toward the opposite car-sides. 15 The doors are normally inclined, and a feature of the invention is the manipulation of the doors in such manner that when opening their inclination is increased by depressing 20 their lower or inner portions and raising their outer portions. Located at the axial line of these oscillating movements are the connections with the door-shifting mechanisms, the arrangement being such that the 25 shifting devices move in horizontal planes, in the present embodiment being actuated by screw shafts extending transversely of the car. Many details involving structural improvements are included in this general plan 30 of operation.

With the doors arranged in accordance with the present invention each door has a definite axis of rotation located at the center of its support and relatively near the 35 center line of the door-supported-load, with such axis moving along such a line (in the present embodiment a horizontal line) as will maintain a constantly freeing angle with regard to the friction of the load on 40 the door.

A further purpose of the invention is to so construct the car body and the doors as to give access to the interior for the purpose of poking and loosening ore or other material which has become frozen, or has from 45 other causes solidified so as to move either sluggishly or not at all when the doors are opened.

A further characteristic of the invention 50 is the mode of constructing the frame of the car, particularly with reference to taking care of the draft forces communicated from the draft beams, whereby an exceptionally strong construction is secured from a relatively 55 small amount of structural material,

this feature possessing the double advantage of minimizing both the cost and the weight.

In the accompanying drawings, Figure 1 is a view partly in side elevation and partly in vertical section of a dump car embodying 60 the invention, the sectional portion of the view being taken through the center of the car. Fig. 2 is a view partly in end elevation and partly in cross section, the sectional part being on line 2-2 of Fig. 1. Fig. 3 is 65 a vertical cross-section on line 3-3 of Fig. 1. Fig. 4 is a sectional plan on line 4-4 of Fig. 1. Figs. 5, 6 and 7 are detail views of the door and door-operating mechanism.

The invention is here shown embodied in 70 a single hopper car, which while designed especially for service in hauling ore, may be modified as required for various services, and the novel features may be incorporated in cars of many different designs. 75

Referring to the drawings, 2 designates the two longitudinal sills of the car, which in the present adaptation are located at the extreme outer sides of the frame and, together with the hopper-inclosing side girders, transmit the draft forces from one end of the car to the other. The sills are preferably in the form of inverted channels; and are here shown terminating at bolsters 3. 80

It is characteristic of the invention that 85 the draft forces are transmitted from the draft beams 5 to longitudinal sills 2 by a novel arrangement of framing which requires a relatively small amount of metal and by which the strength of materials necessary in other features of the construction 90 is utilized which otherwise would be dormant. This is accomplished by two opposed or reversely acting force-transmitting bracings, one in tension and the other in 95 compression, and so arranged that each fully counteracts the other. Strains which otherwise would be excessive are thus neutralized, and hence less metal is required than though either the full tension or compression strain 100 had to be taken care of.

In the construction here shown this feature is embodied in two reversely arranged V-shaped trusses 7 and 4 at opposite sides of bolster 3, the latter constituting a tie or 105 chord common to both, whereby its latent strength—strength not utilized in performing the functions of a bolster—is availed of. Each truss is secured at its apex to draft beams 5, truss members 7 uniting therewith 110

at its juncture with buffer beams 6, and truss members 4 secured to the inner extremities of the draft beams. Compression draft forces are much higher than those communicated in tension, being frequently as high as 500,000 pounds, while the tension forces are seldom above 100,000 pounds. The improved construction provides a very simple and efficient means for taking care 10 of these forces.

The compression forces are communicated to the draft beams through the draft rigging (not shown) connected to the usual draft lugs 5'. The compression strains, im- 15 parted through the draft lugs, place members 7 of the outer truss in compression, with their divergent ends held from parting by bolster 3 which is thereby placed in tension. A reverse action takes place in 20 members 4 of the inner truss, the same forces which place the outer truss in compression setting up tension strains in members 4, and compression strains result in bolster 3. When the draft forces are in tension, the 25 action of the two truss bracings are the reverse of that above described, the outer truss 7 then acting in tension, and inner truss 4 in compression. Hence, whether the draft forces are compression or tension, two 30 independent and reversely acting systems of bracings are always doing duty, and while reverse in action they coöperate in such manner that the compression strains of one system counteract the tension strains of the 35 other, with the result that less frame material is required to transmit the forces than would be necessary if the full compression and tension forces of the bracing had to be taken care of.

40 The upper portions of the hopper-inclosing girders 9 define the maximum width of the car. The lower portions of these girders are deflected inwardly a distance equal to the width of sills 2, thus giving the hopper its slight flare, as shown. The side plates are riveted to the inner flanges of sills 2, and are projected downwardly therefrom a short distance, preferably vertically, as indicated at 10, to form opposite sides of 50 the hopper mouth.

Each end wall of the hopper consists of two slightly separated plates 11 which slope downward and inward, their lower extremities forming the ends of the hopper mouth. 55 The upper portions of these plates are connected by the splice plate 11', and their lower portions by the downward flange 8' of gusset 8, the latter located at the juncture of truss arms 4 and draft beams 5.

60 The doors are normally inclined toward the center-line of the car and are movable bodily in the direction of the car sides when opening and closing, with provision for increasing the inclination of each door as it opens, such increased inclination being had

during the opening movement by lowering the inner portion and simultaneously raising its outer portion. Thus, increased space or clearance is had between the doors when fully open and their angular position is such 70 that the ore or other material flows freely therefrom.

In the present adaptation of the invention the bottom of each door is formed in two planes or parts which are separated vertically to provide poking openings or spaces 75 13, the plane forming the outer or upper portion 14 of the bottom being uppermost and overlapping the lower portion 15 sufficiently to prevent the material being transported from discharging outwardly between 80 the two bottom portions when the doors are closed.

Each of the door structures consists of two upright end members 16, preferably 85 cast, and of general triangular form, the base of the triangle being the inner edge of the end member which stands vertical when the door is closed. The lower edge of the end member is flanged longitudinally at 17 90 and 18, said flanges overlapping each other and separated at the overlap by a vertical offset which forms the poking space 13, above referred to, flanges 17 supporting part 14 of the door floor or bottom, and 95 flanges 18 similarly supporting part 15, parts 14 and 15 consisting of plates which are riveted to the flanges, as shown, which are reinforced at the center by braces 14'. Each of the doors may be provided at its 100 under side with a transverse reinforcement 19, here shown in the form of a channel arranged edgewise, and for securing the same the lower edges of end members 16 may have the downward extensions 20 around 105 which the channel fits.

Each of the doors is, in the design here shown, supported on four wheels, two of the wheels 21 being journaled to bosses 22 projecting from the inner portions of end members 16 near their upper edges, while similar wheels 23 are carried by the outer portions of the end members. The inner wheels 21 travel on the downwardly and outwardly inclined track sections 24. These tracks 110 consist of relatively short pieces of rails which extend through and are supported by the depending loops 25, with the rail inclined downwardly in opposite directions from the loop to sustain the corresponding 115 wheels 21 of the two doors.

The doors are preferably operated by horizontal transverse screw shafts 28 which may be geared together at one side of the car by a connecting shaft 29 to insure 120 unitary movement, and by means of which the whole door manipulating movement may be effected through or by means of an operating wheel 30 on an extremity of one of shafts 28. Each of shafts 28 is opera- 125 30

tively connected to the corresponding ends of the doors through the medium of threaded sleeves 31. Secured to each of these sleeves is a depending arm 32 having a laterally projecting pintle 33 which operates in a bearing 34 formed in the top edge of end member 16 of the door. In the present adaptation, shafts 28 are located behind the end portions of the hopper mouth and in the plane of the draft sills 5, and hence being at one side of the vertical plane of the doors, arms 32 are in inclined position, as shown:

The pivotal connection with the door is made at that point on the latter which moves horizontally as the door opens and closes, or in other words at the horizontally shifting axis of oscillation of the door, so that horizontal movement of sleeve 31 in either direction results in a corresponding inward or outward movement of the door, which movement does not interfere with the vertical oscillation determined by the inclination of tracks 24 and 26. With the center of oscillation shifting horizontally, the outer or upper portion or edge of the door rises more abruptly than its inner portion lowers, and hence tracks 26 have greater inclination than tracks 24. Owing to this the inclination of the doors is greatly increased by the opening movement, affording a wide opening through which the ore or other material is discharged from the relatively steep sides. Furthermore, the arrangement results in holding the doors substantially balanced at all times so that comparatively little force is required to operate them.

To prevent sleeves 31 from binding on the shafts, a traveling guide is provided which may consist of an upward forked extension 35 of arm 32, with a wheel 36 journaled on each extension and traveling in the inclined trough-shaped guide or channel 37 located behind end plates 11 of the hopper. The guide may be slotted longitudinally at 38 and the spindles 39 of wheels 36 projected through the slot and provided with washers 40 on the outer side of the latter. Channel 37 in which the wheels move and slot 38 for the wheel spindles hold sleeve 31 absolutely parallel with shaft 28 so that there can be no twisting or binding, this without interfering in the slightest degree with the longitudinal movement of the sleeve of the shaft.

In addition to the provision for poking the ore or other material through door spaces 13, additional poking openings 41 may be located in side girders 9 wherever they may be found most expedient. Two such openings are here shown in each side of the lower portion of the hopper, with an upwardly bulged pocket-like shield 42 extending upwardly over a greater portion of the opening, said shield being so arranged, also space 13 so formed with relation to bottom parts

14 and 15 of the door, as to inclose the angle of repose of the ore or other material hauled so that the latter will not discharge therefrom. These poking spaces or openings afford ready access for poking or stirring frozen or caked ore or other material which if not broken up tends to retard the flow, and frequently completely obstructs the hopper mouth.

I claim:

1. An inclined bodily movable door for a dump car rotatable about a horizontal axis with said axis fixed relatively to the door approximately midway between its upper and lower edges.

2. An inclined bodily movable door for a dump car rotatable about a horizontal axis with said axis movable with the door and disposed approximately midway between the upper and lower edges of the door, and means for causing said axis of rotation to move horizontally as the door opens and closes.

3. A door for dump cars movable bodily, oppositely inclined supports for the outer and inner portions of the door on which the door moves, the door rotatable about a horizontal axis, and means for moving the axis of rotation in a straight line.

4. A door for dump cars movable bodily, oppositely inclined supports for the outer and inner portions of the door, the door rotatable on a horizontal axis, and means for moving the axis of rotation in a horizontal plane.

5. A door for dump cars movable bodily and rotatable between its inner and outer edges about a horizontal axis, oppositely inclined supports engaged by the door at opposite sides of its axis of rotation and on which the door moves, and means for moving said axis of rotation together with the door.

6. A bodily movable door for dump cars, means for simultaneously moving opposite edges of the door upwardly and downwardly respectively, a screw shaft, a sleeve traveling on the shaft, an arm projecting from the sleeve and pivotally connected to the door, and means co-operating with the arm for preventing the sleeve from cramping on the shaft.

7. Door actuating means for a dump car comprising a screw shaft, a door operating sleeve traveling on the shaft, a guideway paralleling the shaft, and sleeve-holding means movable in the guideway.

8. Door actuating means for a dump car comprising a screw shaft, a door operating sleeve traveling on the shaft, a guideway paralleling the shaft, an arm carried by the sleeve, and wheels on the arm movable in the guideway.

9. Door actuating means for a dump car comprising a screw shaft, a door operating

- 1 sleeve traveling on the shaft, a guideway having a flange and a slot parallel with each other and paralleling the shaft, an arm carried by the sleeve, journal pins secured to the arm and movable in said slot, and wheels on the pins traveling on the said flange.
10. A door for dump cars formed in two relatively fixed parts separated from each other to form a poking space.
11. A door for dump cars formed with relatively fixed outer and inner parts, the outer part being higher than and overlapping the inner part to form a poking space between the parts.
12. A door for dump cars consisting of two upright end members each flanged longitudinally with a vertical offset in the flange intermediate its ends and with the flange parts overlapping at the offset, and plates secured to the flanges and spaced 20 apart by the flange offsets to form a poking space.
13. A door for dump cars consisting of two upright end members flanged longitudinally, plates secured to the flanges, wheels 25 mounted on the end members, supports on which the wheels move for opening and closing the door, and door moving means.
14. A dump car having poking openings in the sides thereof above the doors, doors 30 for dumping the contents of the car, and poking openings in the doors.

In testimony whereof I affix my signature in presence of two witnesses.

CHARLES H. CLARK.
